CLAIM

The ornamental design for a coin holder, as shown and described.

DESCRIPTION

FIG. 1 is a top, front, right side perspective view of a coin holder showing my new design;

FIG. 2 is a bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded bottom, rear, left side perspective view of the coin holder.

The broken lines in the drawings depict portions of the coin holder that form no part of the claimed design.
